UNITED STATES PATENT OFFICE.

LEWIS W. CHUBB, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

ELECTRIC-RESISTANCE DEVICE.

1,267,973.

Specification of Letters Patent.

Patented May 28, 1918.

Application filed January 6, 1915. Serial No. 798.

To all whom it may concern:

Be it known that I, LEWIS W. CHUBB, a citizen of the United States, and a resident of Edgewood Park, in the county of Allegheny and State of Pennsylvania, have invented a new and useful Improvement in Electric-Resistance Devices, of which the following is a specification.

My invention relates to electrical resistance devices for rheostats, heating apparatus and the like, and it has for its object to provide resistance devices with effective and rapidly-operating cooling means, and thereby to greatly decrease the weight and bulk of such resistance devices in proportion to the energy which they are designed to dissipate.

One modification of my invention is illustrated in the accompanying drawing, in which Figure 1 is a diagrammatic view illustrating a system for cooling the secondary control rheostats of a polyphase induction motor, Fig. 2 is an elevational view of one of the resistance elements employed in the system shown in Fig. 1, and Fig. 3 is an end view of the structure shown in Fig. 2.

Resistance elements that are commonly employed in the electric arts are usually composed of air-cooled metallic coils or grids, and, in large installations, their aggregate weight often amounts to many tons and their bulk to many cubic yards, on account of the relatively low current density that is permissible in grids which are cooled by means of air currents. Attempts have been made to cool resistance grids with oil or with circulating water, in order to increase the permissible current density and to correspondingly decrease the necessary weight and size of the grids. It is found, however, that but little economy is effected by these methods over those which are incident to the use of ordinary air-cooled structures. The use of oil is limited because of fire hazards, and the use of water or other conducting liquids has heretofore been limited because of electrolysis or because of the inefficient transfer of heat between the resistance elements and the liquid when insulating coverings are used to prevent electrolysis.

I have discovered that, if resistance elements are provided with electrolytically formed insulating films, they are well adapted to be rapidly cooled by means of water or

other liquids because of the low heat gradient through the film of insulation. Metallic bodies provided with such electrolytically applied insulating coatings are called polarized bodies.

It is well known that certain metals, notably aluminum, but also including platinum, magnesium, tantalum and other metals, may be provided with electrically insulating films by immersing them in a suitable electrolyte and subjecting them to an electric current. The films thus formed, which consist of the hydroxids or some other compounds of the metals, are asymmetric insulating coatings. That is to say, they permit current to flow from the electrolyte to the coated metal, but strongly resist the flow of current from the metal to the electrolyte, and metals which can be so provided with insulating coatings are termed film-forming metals. These films, which are exceedingly thin, possess high specific resistance and high dielectric strength, and are therefore able to withstand high voltages without rupture. Such films, however, offer but little resistance to the passage of heat, and therefore readily dissipate heat generated in the metal, either electrically or otherwise. My invention is based upon these properties of aluminum and other metals, and contemplates the manufacture of electric resistance elements which are composed wholly or superficially of aluminum or of some other film-forming metal and which are provided with means for applying cooling fluids to them.

The film-forming metals may be provided with insulating coatings by electrolysis in a bath of any one of a number of electrolytes, such, for example, as an aqueous solution of borax and boric acid. Some electrolytes which are suitable for this purpose are described and claimed in my copending application, Serial No. 864,666, filed Oct. 2, 1914, and assigned to the Westinghouse Electric and Manufacturing Company. Any of the electrolytes described therein and many other suitable film-forming electrolytes may be used in practising my present invention.

On account of its cheapness, aluminum is ordinarily preferred as the film-forming metal to be used in my process, and the resistance elements may be either composed entirely of aluminum or formed of a core of

a non-film-forming metal provided with a coating of aluminum. The cooling liquid may be water or any other desired cooling liquid, but I prefer to employ, as the cooling liquid, a solution of a film-forming electrolyte, in order that any breaks that may occur in the insulating film upon the resistance elements, by reason of mechanical shocks or electrical rupture, may be automatically and 10 immediately repaired.

The accompanying drawing illustrates the application of my invention to the cooling of the control resistors in the secondary circuit of a three-phase induction motor. The 15 primary and secondary windings of the motor are indicated diagrammatically at 1 and 2, and phase conductors 3 connect the secondary winding 2 with resistors 4, 5 and 6, which are electrically star-connected at the 20 point 7. The resistance elements 4, 5 and 6, are inclosed within a tank 8 provided with an outlet opening 9 that is connected, by means of a pipe 10, to a cooling coil 11 contained within a tank 12 which should preferably be disposed at a higher level than the top of the tank 8. The tank 12 is provided with inlet and outlet pipes 13 and 14 by means of which water or other fluid can be circulated through the tank 12, and 25 the cooling coil 11 is connected, by means of a pipe 15, to an inlet opening 16 in the tank 8. The tank 8 contains a body of liquid 17, which may fill the tank either partly, as shown, or completely. This liquid 30 may be water or any other desired cooling liquid, but, as stated above, I prefer that it shall contain a film-forming electrolyte. If the liquid 17 fills the tank 8 only partly, as shown in the drawing, the heat generated 35 in the resistors 4, 5 and 6 will vaporize the liquid, and the vapor will be conducted through the opening 9 and the pipe 10 to the cooling coil 11, which is kept cool by a circulation of water or other cooling fluid 40 through the tank 12, and the liquid condensed in the coil 11 will be returned through the pipe 15 to the inlet opening 16 of the tank 8. If the amount of liquid 17 is sufficient to fill the tank 8 and the coil 11, the 45 heated liquid will itself circulate through the pipe 10, cooling coil 11 and return pipe 15. In this case, a safety outlet should be provided for the coil 11 in order to prevent 50 damage to the pipe connections by reason of excessive steam pressures or thermal expansion of the liquid.

The coil 11, instead of being a cooling coil immersed in a tank of fluid, may be a steam or hot water radiator, which may be 55 located remotely from the tank 8 and freely exposed to the air. In this application of my invention, the heat liberated from the coils 4, 5 and 6 may be used for heating apartments and the like and may thus be 60 fully utilized.

Each of the resistance members 4, 5 and 6 may be constructed in the manner shown in Fig. 2, which shows a core 20 of film-forming conducting material supporting a series of strips 21 of wood or other non-conducting material upon which is non-inductively wound a conductor wire 22, preferably of aluminum. One terminal of the coil 22 is attached to the conducting body 20 at 23, and the other terminal 24 is adapted to be 75 connected to the neutral point 7 of the star-connection. The conducting body 20 extends through a suitable packing device 25 disposed in the wall of the tank 8 and is provided with a suitable terminal 26 which 80 is secured in place by means of nuts 27.

The arrangement shown in the drawing is well adapted for use in connection with the large electric machines employed in naval service, in which case the tank 12 may be 85 supplied with a constant current of sea water. It is to be noted that, while the energy developed in the resistance members is dissipated by means of sea water, the water itself does not come into contact with such members. Leakage currents and dangerous 90 stresses between the resistance elements and the highly conducting sea water are thereby avoided.

The system described above is particularly 95 well adapted for use in cooling resistance elements that are inserted in direct-current circuits and for cooling the control resistors of induction motors where the frequency is low and where electrolysis is a source of 100 serious trouble when the resistors are cooled with electrically conducting liquids.

My invention is capable of numerous other 105 applications in addition to those just described. For example, testing rheostats embodying my invention may be substituted for the present equipments which now include water rheostats and air cooled racks. A saving in cost, space and weight may thus be effected and the dirt, corrosion and electrical oscillations of the water rheostat be avoided. My invention also finds application in electric steam boilers for heating 110 purposes and for the generation of steam for heating or for motive power. All such modifications and adaptations are comprehended within the scope of my invention, which is therefore to be limited only by the 115 scope of the appended claims.

I claim as my invention:

1. An electric resistance element provided with a covering which acts as an electrical insulator but has substantially no heat-insulating effect.
2. An electric resistance device comprising a resistance element provided with a covering which acts as an electrical insulator but has substantially no heat-insulating effect, and means for surrounding the said resistance element with a cooling fluid.

3. An electric resistance element comprising a body of film-forming metal provided with an electrolytic insulating film.
4. An electric resistance element comprising a body of aluminum provided with an electrolytic insulating film.
5. An electric resistance device comprising a resistance element having a surface covered with an electrolytic insulating film, and means for surrounding the said resistance element with a cooling fluid.
6. An electric resistance device comprising a resistance element having a surface covered with an electrolytic insulating film, means for surrounding the said resistance element with a cooling fluid, and means for removing heat from the said fluid.
7. An electric resistance device comprising a resistance element having a surface covered with an electrolytic insulating film, and means for surrounding the said resistance element with cooling liquid containing a film-forming electrolyte.
8. An electric resistance device comprising a resistance element having a surface covered with an electrolytic insulating film, means for surrounding the said resistance element with a cooling liquid containing a film-forming electrolyte, and means for removing heat from the said liquid.
9. An electric resistance device comprising a resistance element having a surface covered with an electrolytic insulating film, a casing for inclosing the said element, and means for causing cooling fluid to circulate through the said casing.
10. An electric resistance device comprising a resistance element having a surface covered with an electrolytic insulating film, a casing for inclosing the said element, and means for causing a cooling liquid containing a film-forming electrolyte to circulate through the said casing.
11. An electric resistance device comprising an aluminum resistance element covered with an electrolytic insulating film and means for surrounding the said resistance element with a cooling fluid.
12. An electric resistance device comprising an aluminum resistance element covered with an electrolytic insulating film and means for surrounding the said element with a cooling liquid containing a film-forming electrolyte.
13. An electric resistance device comprising a resistance element having a surface covered with an electrolytic insulating film, a liquid-containing casing for inclosing the said element, a second casing containing a cooling coil, means for effecting communication between the said cooling coil and the said first-named casing and means for causing cooling liquid to circulate through the said second casing.
14. An electric resistance element comprising a core of conducting material, a coil of resistance material surrounding the said core and provided with an electrolytic insulating film, and spacing strips of non-conducting material interposed between the said core and the said coil.
15. An electric resistance element comprising a core of conducting material, a coil of polarized resistance material wound non-inductively around the said core and electrically connected to the said core, and spacing strips of non-conducting material interposed between the said core and the said coil.
16. An electric resistance device comprising a resistance element submerged in an electrically conducting cooling liquid and polarized to prevent current from leaving the said resistance element and flowing through the said cooling liquid.
- In testimony whereof, I have hereunto subscribed my name this 31st day of Dec. 1914.

LEWIS W. CHUBB.
